US00D824761S

(12) **United States Design Patent** (10) Patent No.: **US D824,761 S**
(45) Date of Patent: ** Aug. 7, 2018

(54) **DISPENSER**

(71) Applicant: **Clariant Healthcare Packaging (France) SAS**, Choisy le Roi (FR)

(72) Inventors: **Jacquy Lebon**, Challands (FR);
Dominique Bois, Montreuil aux Lions (FR)

(73) Assignee: **CLARIANT HEALTHCARE PACKAGING (FRANCE) SAS**, Choisy le Roi (FR)

(**) Term: **15 Years**

(21) Appl. No.: **29/581,067**

(22) Filed: **Oct. 14, 2016**

(30) **Foreign Application Priority Data**

Apr. 14, 2016 (EM) 003068568

(51) LOC (11) Cl. **09-07**

(52) U.S. Cl.

USPC **D9/447**

(58) **Field of Classification Search**

USPC D3/202, 203.1, 242; D7/316, 321, 392.1, D7/396.2, 397, 500, 507, 509-511; D9/434-437, 439, 440, 442-445, 447, D9/448, 449, 450, 452-455, 499, 682, D9/685, 694; D23/213, 227, 233, 255, D23/260, 269, 390

(57) **CLAIM**

We claim the ornamental design for a dispenser, as shown and described.

DESCRIPTION

FIG. 1 is a bottom perspective view of a dispenser showing my new design;

FIG. 2 is a top perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof; and,

FIG. 9 is a cross-sectional view thereof, taken in the direction of line 9-9 in FIG. 8 drawing view.

The broken lines in the drawings illustrate portions of the dispenser that form no part of the claim.

1 Claim, 9 Drawing Sheets
